UNITED STATES PATENT OFFICE.

DANIEL H. WRIGHT, OF LANSINGBURG, NEW YORK.

ADJUSTABLE PICKER-STAFF CHECK.

SPECIFICATION forming part of Letters Patent No. 591,122, dated October 5, 1897.

Application filed September 9, 1896. Serial No. 605,319. (No model.)

To all whom it may concern:

Be it known that I, DANIEL H. WRIGHT, a citizen of the United States, residing at Lansingburg, in the county of Rensselaer and 5 State of New York, have invented a new and useful Adjustable Picker-Staff Check for Looms, of which the following is a specification.

This invention relates to picker-staff checks 10 for looms; and it has for its object to provide an adjustable device of this character adapted for use in connection with the picker-staff or lever of the loom to provide simple and efficient means for checking and holding the 15 picker-staff to prevent the tendency of the shuttle to rebound and break the threads, which is of considerable importance in looms and is a result not always positively secured by the leather checks or straps commonly employed.

With these and other objects in view, which will readily appear as the nature of the invention is better understood, the same consists in the novel construction, combination, 25 and arrangement of parts hereinafter more fully described, illustrated, and claimed.

In the drawings, Figure 1 is a perspective view of a portion of a loom equipped with the check attachment constructed in accordance 30 with this invention. Fig. 2 is a bottom plan view of the end portion of the lay-beam carrying the check attachment. Fig. 3 is a transverse sectional view on the line 3 3 of Fig. 2.

Referring to the accompanying drawings, 35 1 designates a loom of any approved construction, having the usual lay-beam 2, provided at its end with the longitudinally-disposed slot 3, in which plays the upper end portion of the picker-staff or lever 4, which is operated in the usual manner to provide for driving the shuttle 5^a back and forth along the race of the lay-beam. Ordinarily provision is made for checking the outward movement of the picker-staff 4 to prevent rebounding 40 thereof and a consequent rebounding of the shuttle, so that when it (the shuttle) is struck the next time it does not get the full force of the blow, and the result is a broken thread. To provide for this necessary checking of the 45 picker-staff, the present invention contemplates the use of a pair of duplicate flat spring

check-plates 5, arranged at one end of the lay-beam 2, below said beam, and secured fast at their inner ends, as at 6, to opposite sides of a depending attaching-block 7, suitably secured to the under side of the lay-beam in line with the longitudinally-disposed slot 3 for the picker-staff.

The flat spring check-plates 5 are of sufficient length to permit of the requisite play 60 for the picker-staff and are disposed oppositely to each other in the same horizontal plane, so as to be arranged, respectively, at opposite sides of the picker-staff 4, which is designed to play between said plates and to become frictionally gripped thereby at the outer limit of its movement.

The opposing flat faces of the check-plates 5 are disposed in vertical planes, so as to flatly contact with the opposite sides of the picker-staff, and the outer movable ends of the plates 5 are normally disposed closer together than the thickness or width of the picker-staff 4, so that said picker-staff on its outward movement must necessarily force its way in 75 between the said outer movable ends of the check-plates.

The outer movable ends of the check-plates 5 are located immediately below the adjacent outer end of the lay-beam 2, between a pair 80 of parallel pendent beam-ears 8, projected from the under side of the lay-beam at the end thereof and located, respectively, at opposite sides of the slot 3, in which the picker-staff works. The pendent beam-ears 8 are 85 provided on their outer sides with the off-standing socket projections 9, open at their inner ends and having in their outer closed ends the bolt-openings 10, loosely receiving therein the outer threaded portions 11 of the adjusting-bolts 12, the inner head ends 14 of which are fixedly fitted in the movable end portions of the oppositely-located spring check-plates 5, which check-plates, it will be understood, are preferably made of steel 95 spring, so as to have the requisite resiliency. The threaded portions of the adjusting-bolts 12 extend through the bolt-openings 10 of the socket projections 9, and receive thereon the adjusting-nuts 15, working against washers 100 16^a, arranged on the outer ends of the said socket projections 9. Coiled cushion-springs

16 are arranged inside of the socket projections 9 and encircle the bolts 12, with their ends respectively bearing against the outer sides of the plates 5 and the outer closed ends 5 of the socket projections 9. The springs 16 normally hold the movable ends of the plates 5 as close together as required, while at the same time cushioning the outward movement of the said movable ends of the check-plates, 10 so as to retain the said check-plates in firm frictional contact with the opposite sides of the picker-staff 4 when forced therebetween. By manipulating the nuts 15 the normal distance between the movable ends of the plates 15 5 may be varied to suit the sides of the picker-staff 4 as the same become worn by use.

In operation the picker-staff 4 plays between the spring-plates 5 and on its outward movement is forced between and frictionally 20 held by the movable ends of the check-plates until the next blow drives it back.

It will be observed that the construction insures the check-plates exerting a gradual tightening pressure on the picker-staff, so as 25 not to materially interfere with its movement, while at the same time preventing any rebound and permitting of the easy release of the staff or lever.

Changes in the form, proportion, and the 30 minor details of construction may be resorted to without departing from the principle or

sacrificing any of the advantages of this invention.

Having thus described the invention, what is claimed, and desired to be secured by Letters Patent, is—

In a picker-staff check for looms, the combination of the lay-beam provided below and at opposite sides of its slot with offstanding socket projections formed with bolt-openings 40 in their outer ends, a fixed attaching-block arranged at the under side of the beam, a pair of duplicate flat spring check-plates arranged respectively at opposite sides of the picker-staff and fixedly fastened at one end 45 to said attaching-block, the unattached ends of said plates being normally disposed closely together, adjusting-bolts arranged in said socket projections and connected at their inner ends with the movable end portions of 50 said plates, nuts engaging the outer portions of the bolts exterior to the socket projections, and springs coiled on the bolts within the socket projections, substantially as set forth.

In testimony that I claim the foregoing as 55 my own I have hereto affixed my signature in the presence of two witnesses.

DANIEL H. WRIGHT.
